UNITED STATES PATENT OFFICE.

JOHN W. GHEEN, OF LOS ANGELES, CALIFORNIA.

CUTTING-OFF TOOL.

1,058,360.

Specification of Letters Patent. Patented Apr. 8, 1913.

Application filed November 16, 1911. Serial No. 660,738.

To all whom it may concern:

Be it known that I, JOHN W. GHEEN, a citizen of the United States, residing at Los Angeles city, in the county of Los Angeles, State of California, have invented a new and useful Improvement in Cutting-Off Tools, of which the following is a specification.

My invention more particularly relates to providing a means of adjusting and securing the cutting of a cutting off tool blade perpendicular to the cut.

Reference is to be had to the accompanying drawing in which—

Figure 1 is a plan view of the tool. Fig. 2 is a perspective view of the clamp. Fig. 3 is a sectional view through the center of the binding clamp and screw.

Similar letters refer to similar parts throughout the several views.

A is that portion of the tool by which it is secured, when in use and is made in such proportions that it will fit the ordinary tool post. Between the head of the tool and the shank is the slot M, partially dividing the head from the shank forming the spring G' so that when under an undue strain the blade D has a tendency to spring away from the cut, the bottom of the blade is given a bearing the entire length of the head O, and on a part of the shank A, at P.

The blade D is secured by the binding clamp F, held in position by the binding screw G, the lower part of the blade rests on the longitudinal projection E and with the bottom of the cutting blade forms a pivot, for the blade adjustment. The top of the

blade is held in a shallow groove I, in the blade clamp, transversely to this groove is a tongue K, arranged to slide in a slot in the 40 tool head. A slot hole H in the binding clamp allows a movement to the top of the cutting blade, so that the clearance on either side of the blade may be equally divided, an essential feature in a tool of this class. 45 When it is desired to give the cutting blade the proper alinement the binding screw G is loosened and the binding clamp is moved till the proper alinement is obtained, not only is the proper alinement given to the 50 blade, but the projection of the cutting blade may be shortened or lengthened.

The semicircular recess J, in the spring slot is provided as a receptacle for a semi-solid substance, to prevent underchattering 55 when the tool is under strain.

What I claim and desire to secure by Letters Patent is,

The combination with a head having a blade supporting flange of a clamp coacting 60 with the said flange to clamp a blade therebetween said clamp being provided with a groove to receive a longitudinal edge of said blade and with a slot extending at right angles to said groove, and a set screw passing through said slot, and having a screw threaded engagement with said head. 65

In witness whereof, I have hereunto affixed my signature in the presence of two witnesses.

JOHN W. GHEEN.
